Primary Examiner—Lisa Lichtenstein

(21) Appl. No.: **29/275,284**

(57)

CLAIM

(22) Filed: **Dec. 20, 2006**

The ornamental design for a fan, as shown.

(30) **Foreign Application Priority Data**

Jul. 28, 2006 (EM) 000566906-0004

(51) **LOC (8) Cl.** 23-04

FIG. 1 is a perspective view showing my design;

(52) **U.S. Cl.** **D23/382**

FIG. 2 is a front elevational view thereof;

(58) **Field of Classification Search** D23/382,

FIG. 3 is a rear elevational view thereof;

D23/381, 332, 370, 328, 335, 336, 337, 412,

FIG. 4 is a right side elevational view thereof;

D23/411; 416/246 R, 247 R, 244 R

FIG. 5 is a left side elevational view thereof;

See application file for complete search history.

FIG. 6 is a top plan view thereof; and,

(56) **References Cited**

FIG. 7 is a bottom plan view thereof.
